UNITED STATES PATENT OFFICE

2,667,998

BOTTLE CAPPING MACHINE

Arthur Graham Enock, London, England, assignor to Graham-Enock Manufacturing Company Limited, London, England

Application April 2, 1951, Serial No. 218,727

Claims priority, application Great Britain April 3, 1950

15 Claims. (Cl. 226—85)

1

This invention relates to bottle filling and capping machines such as milk bottling machines wherein a cap making unit is provided by which aluminum or other foil caps are punched out of a strip of aluminum or other foil and delivered to a cap release mechanism from which they are picked up by the travelling bottles as they pass to the capping unit. A bottling machine of this type is described in the specification of my prior application Ser. No. 51,778, now Patent No. 2,597,791, issued May 20, 1952.

An object of the present invention is to provide an improved arrangement of the cap forming unit whereby a simplified form of drive is provided and the unit is mounted in a position facilitating access to the cap delivery and foil feeding and loading.

According to the invention the cap forming unit is mounted above the capping head and is operated by a rotary element thereof.

The cap forming unit may be supported by the stationary central element of the capping unit such element supporting the head and being adjustable as to height for accommodating different sizes of bottles.

A drive to the operative parts of the cap forming unit may be effected by a gear wheel secured to the rotary head of the capping unit and engaging a pinion or a driving shaft on the cap forming unit.

The driving shaft is adapted to drive a driven shaft through a clutch means which are intermittently put in only when a bottle is in capping position.

In the accompanying drawings:

Figure 1 is a plan of a bottle filling and capping machine with the improved cap forming unit applied thereto.

Figure 2 is an elevation, partly in section, on the line 2—2 of Figure 1.

Figure 3 is an elevation, partly in section, on the line 3—3 of Figure 1.

Figure 4 is an elevation, partly in section, on the line 4—4 of Figure 1.

Figure 5 is a section elevation of a sealing head.

Figure 6 is a sectional elevation of a preferred form of cap forming unit.

Figure 7 is a sectional elevation (at right angles to Figure 6) of the punch and cap operated actuator.

In carrying the invention into effect according to one convenient mode as applied to a capping unit of the character described in the specification Ser. No. 51,178, now Patent No. 2,597,791,

2

the upper rotary sleeve 1 of the capping head 2 is extended upwardly and formed with a cup part 3 open at its upper end and coaxial with the head. Secured to the base wall 4 of the cup 3 is a ring 5 which encloses an upper ball bearing 6. The ring 5 is rebated at the upper edge to receive a gear wheel 7 which is secured with the ring to the base 4 by screws 8.

The stationary central column or spindle 8a of the capping head projects beyond the bearing 6 and has keyed to it by a key 9, a supporting plate 10 which is secured to the spindle by a central fixing plate 11.

The plate 10 supports the cap forming unit 12 the mounting 13 of which has a base plate 14 which is recessed to receive an upwardly projecting spigot 15 on the plate 10 so that the cap forming unit may be turned about the axis of the column 8a when required. The base plate 14 has an aperture to receive the fixing plate 11. The cap forming mounting and gear unit is held onto the supporting plate 10 by a shouldered stud 16 which is cut away so that the narrow portion is within the width of the slot to allow removal 25 of the gear unit.

The cap forming unit 12 has a downwardly extending bell shaped portion 18, the lower wall 19 of which is cylindrical and is located outside the cup part 3 forming therewith an enclosing 30 casing for the operative gear of the cap forming unit.

The operative gear is carried by the mounting 13 which at its upper part supports a reciprocating die unit 20 for cutting out the caps from a strip of aluminum 21. The die unit 20 extends above and below the bell 18 and in the lower part a plunger 22 is guided which is operated by a rotary cam 23 which engages a roller 24 on the plunger.

The cam 23 is fixed on a horizontal shaft 25 having bearings 26 in the mounting 13. The shaft 25 is driven by bevel gear 27 from a vertical stub shaft 28, supported in the bearing 29 on the mounting 13. The stub shaft is adapted to be driven by a driving pin 30 supported in bearing 31 on mounting 13 and axially in line with the stub shaft.

Extending downwardly and axially through the stub shaft 28 is an axially displaceable driving pin 33 which is keyed to a sleeve 30 by a sliding key means.

The driving pin 33 at its lower end is keyed or pinned to a pinion 32 meshing with the gear wheel 7. The stub shaft 28 is provided with a clutch member 34 which is conveniently formed in one

with the bevel gear 27a. Co-operating with this clutch member is a clutch element 35 which is pinned to the driving pin 33. The clutch element 35 is adapted to engage with the clutch member 34 by a vertical displacement of the pin 33 which is effected by a rising movement of a sealing head 36 by the presence of a bottle 37 in position on the appropriate platform 38. The sealing head 36 is mounted for limited vertical sliding movement in a plate 105 supported on the rotary capping head 2. Thus there will be no drive of the cam when a bottle is not in position.

The sealing head 36 in its rising movement in the bearing 39 pivots a lever 40 which in turn by its engagement with the lower end of a thrust pin 41 mounted for sliding movement in the bearing 42, lifts the thrust pin 41.

The thrust pins 41 are adjustable for length.

A plurality of the displaceable thrust pins 41 is provided according to the number of sealing heads 36 and the upper ends of these pins are adapted to engage a flat ring 43, the upper surface of which is engaged by the lower end of the pin 33.

It will be appreciated that the thrust pins 41 rotate with the capping head while the pin 33 remains stationary with the cap forming unit and thus the ring 43 forms an operative connection between the pin 33 and each thrust pin 41 in turn.

The ring 43 is pivotally mounted at one point 44 with a downward radial extension 45 of the ring 5 while at the diametrically opposite point the ring 43 is guided by guiding screw 46 in another downward radial extension 47 of the ring 5.

On the end of the cam spindle opposite to the bevel gear 27 a crank arm 48 is mounted having a crank pin 49 which is coupled by a link 50 to a pivoted pawl arm or plate 51 the pawl 52 of which engages a ratchet wheel 53 on a shaft 54 which carries a sprocket wheel 55, the chain 56 of which engages a pair of sprocket wheels 57, 58, secured on stub shafts 59, 60 mounted on the mounting 13. Each stub shaft 59 and 60 has secured thereto a gear 62, 63 respectively.

The chain 56 also engages a guide sprocket wheel 61 freely mounted on the spindle 25.

The gear 62 meshes with an idle gear 64 which in turn meshes with a gear 65 secured on a spindle 66 which also carries a foil feed roll 67. The spindle 66 and that of the idle gear 64 are supported in bearings in bell 18 or an extension 68 thereof. Co-operating with the feed roll 67 is a spring biased pressure roll 69.

On the opposite side of the bell 18 a second feed drum 70 is provided which drives the scrap strip 21a after the strip 21 has passed through the punching and forming die unit 20. This second feed drum 70 with which a pressure roll 71 co-operates is driven by a gear 72 from the idle gears 73, 74, from the gear 63 on the stub shaft 60.

The gears 72, 73 and 74 and feed roll 70 and pressure roll 71 are supported by the extension 75 of the bell 18.

By this arrangement of drives for the foil and scrap feed rolls 67, 70, the bell 18 with the gears carried thereby may be readily removed when necessary without affecting the chain and sprocket drive.

Foil strip 21 is drawn from a reel 76 by way of a tensioning guide roll 77, such reel being mounted in a bracket 78 secured to the bell 18.

The scrap strip 21a extends backwardly over the upper part of the die unit 20 to a rewind 75

wheel 79 on the bracket 78 and driven by a belt 80 from a pulley 81 on the spindle of the feed drum 67.

Adjacent the drive for the scrap strip a cap chute 81a is supported by the bell 18 and extends downwardly more or less vertically and at its lower end supports cap release means 82 whereby the lowest cap 83 will be located in the path of the bottles so that caps 83 will be picked up as they travel past said means.

At the upper end the chute 81a is flared to receive the caps as they separate from the scrap strip.

The cap forming unit 12 is capable of rotary movement relatively to the supporting column 8a so that it may be swung to a position for convenient access to the cap delivery chute and the foil feed and loading.

For this purpose the bell 18 has secured to it an arcuate ledge 84 which has an undercut groove 85 to receive the heads of bolts 86 which extend through apertures in a plate 87 so that tightening of the nuts 88 grips the plate and ledge.

The plate 87 is perforated to engage a steady-ing post 89 secured to the base 90 of the machine. The post may be graduated for various heights of bottles so that the raising or lowering of the capper head 2 to the desired position may be readily determined by the position of the plate 87 relatively to the graduations.

The invention is shown in association with a bottling and capping machine as described in my patent specification Ser. No. 51,778, now Patent No. 2,597,791, comprising a conveyor 91 which delivers the empty bottles to a transfer wheel 92 by which the bottles are fed to a vacuum filling unit 93, which is connected to the vacuum producing means 94. The filled bottles are transferred by transfer wheel 95 to the platforms 38 of the capping unit 2 and after receiving a cap and being sealed are transferred by transfer wheel 96 to the conveyor 91. The platforms 38 are raised to engage the bottle with the caps in position with the sealing heads 36 by the engagement of rollers 97 in the platform posts 98 with a cam element 99 which is pivotally anchored to the mountings for the transfer wheels 95 and 96. The free end 100 of the cam element is bifurcated and bears upon the shoulder 101 of a resilient supporting post 102.

The various units are supported on the base 90 and driven by operative mechanism located beneath the base.

In operation, as the capper head 2 rotates the gear wheel 7 secured thereto drives the pinion 32 and the driving pin 33.

As a bottle with a cap in position thereon rises in the capping position it lifts the sealing head 36 and causes a lifting of the thrust pin 41 which thereby raises the driving pin 33 to clutch the driving pin to the bevel gear 27a and thus rotates the cam shaft 25.

Through the crank arm 48, link 50 and plate 51 a driving stroke is imparted to the pawl 52 whereby a feeding movement is imparted to the foil feeding roll 67 and the take-up roll 70 for the scrap. During the following stationary period, i. e. the reverse non-driving stroke of the pawl 52 the cam 23 operates to actuate the cap punching and forming dies of the unit 20.

Thus the feeding of the foil strip 21, the take-up of the scrap 21a and the operation of the die unit 20 are intermittent and only take place when a bottle is located in the capping position.

In order that the foil feed and die unit may be

turned over or manually operated when no bottles are being delivered to the capping head, the clutch between 34 and 35 may be held in by raising the driving pin 33 and holding it in its upper position by the spring catch 103 and bell crank lever 104 which engages a cross piece 105a on the driving pin 33.

In the preferred form of the cap forming or die unit (see Figures 6 and 7) an upper die, cap forming and embossing assembly 110 is mounted in the head 111 and projects into a throat 112 in the head, through which the metal strip travels. Beneath the assembly 110 a punch assembly 113 is mounted in the head 111, in axial alignment with the assembly 110.

The punch assembly 113 comprises an inner embossing presser element 114 slidable within an annular punch or die 115. The die element is mounted to slide within a bushing 116 seated in the head 111.

At the lower end of the punch 115 a washer 117 is secured which is provided with a diametral slot 118. Centrally arranged in this washer element is a punch actuator 119 which is adapted to engage the cam 23. Actuator 119 is provided with a threaded screw whereby it may be bolted to the washer element by the nut 120, washers 121 being provided on either side of the fastener 117 to bridge the slot 118 therein.

The embossing element 114 at its lower end is provided with a pair of diametrically disposed extensions 122 which extend through the slot 118 in the washer 117 and, in the down position, as shown in Figure 6, seat upon a stop bracket element 123 which is secured to the head 111 by screws 124. The stop bracket is provided with an aperture 125 through which the actuator 119 projects.

The embosser element 114 intermediate its ends is split by slots 126 to provide a resilience whereby it is frictionally gripped within the die element 115.

The washer 117 engages spring biased returning elements 127 mounted in the head 111 whereby the actuator is held in engagement with the cam 23.

In the upper assembly 110 an inner embossing die 128 is rigidly carried by a stem 129 which extends through a sleeve 130. Concentric with the sleeve 130 is a cap forming element 131, the lower end of which is outwardly radiussed for turning over the rim of the cap. At its lower end the former 131 is enclosed within a die ring 132 which is adapted to co-operate with the die member 115, resiliently to grip a cut out disc. The die ring 132 has a slightly tapered aperture so that it only engages the forming element 131 at the lower end thereof for a purpose to be hereinafter referred to.

The die ring, at its upper end, is outwardly flanged at 133 to seat upon a shoulder 134 in the annular cutting die element 135. The flange is pressed on to this shoulder by a spring 136.

The former element 131 at its upper end is provided with an outwardly extending flange 137 which seats upon a shoulder 138 formed in a guide ring 139 which is seated within the die element.

The former is provided with an inwardly directed shoulder 140 upon which a washer 141 seats, the washer being spring pressed by spring 142, the upper end of which engages a cap 143.

The upper assembly 110 is removable from the head 111 so that the embossing die 128 may be replaced by another die according to the lettering 75

to be impressed in the bottle cap. For this purpose the assembly is held in position by a clamp arm 144 which is mounted upon a sleeve 145 slideable within a recess 146 in the head. The sleeve surrounds a bolt 147 whereby the clamp may be forced down on to the assembly by the nut 148.

The clamp arm has a leather washer 149 adapted to engage a protuberance on the nut 150 which holds the embossing die in position. 10 The clamp arm forms a guide for the scrap strip of foil.

In operation, when the cam 23 rotates it raises the actuator 119 and moves the embosser element 114 and punch die 115 together until the strip of foil is gripped between the punch die element 115 and the die ring 132. At this time a leather washer 160 in the element 114 presses the strip of foil against the embossing die 128 and the element 114 is then held against further

20 movement. The punch die 115 continues to rise so that the die ring is lifted and a disc is cut out of the strip by the engagement of the outer edge of the punch die 115 with the inner edge of the cutting die 135. The punch die and the die ring continue to rise while resiliently gripping the punched out disc which by its engagement with the outer rounded edge of the former 131, has its rim formed to the desired shape.

On the return movement of the parts the die 30 ring 132 acting as a stripper element removes the formed cap from the former 131 so that it rests upon the washer element 160. The parts 114 and 115 then are lowered together under the action of the spring plungers 127 until the extensions 35 122 at the lower end of 114 engage the stop bracket 123 so that relative movement again occurs between 114 and 115 to bring their upper edges into alignment at which time the actuator 119 will be riding on the lower part of the cam 23.

I claim:

1. In combination a bottle capping unit and a cap forming assembly, said capping unit including a stationary spindle and a rotary member surrounding the spindle and concentric therewith, said cap forming assembly including a mounting for a foil feed means and a die means, said mounting being located above said stationary spindle and secured thereto and supported solely thereby, and transmission means between the rotary member and the foil feed means and die means, whereby the cap forming assembly is driven from the capping unit.

2. In combination a bottle capping unit and a cap forming assembly, said capping unit comprising a vertical stationary spindle, a rotary member coaxial with and surrounding said spindle, a series of sealing heads carried by said rotary member, bottle supporting means carried by said rotary member, means for raising said

55 bottle supporting means relatively to said heads, a gear wheel coaxial with said spindle secured upon said rotary member, said cap forming assembly comprising a mounting, foil feed means carried by said mounting, die means for forming caps from a strip of foil fed by said feeding means, driving means carried by said mounting for driving the die means and foil feeding means, said mounting being located above and secured to said stationary spindle, said driving means including a gear pinion meshing with said gear wheel, and clutch means between the driving means and the foil feed and die means, said clutch means being actuated to provide a drive to the capping assembly by a vertical displacement

60 of a capping head when in the capping position.

3. The combination as claimed in claim 2, wherein the driving means for the cap forming assembly includes a cam shaft, a cam on said shaft for actuating said die means, crank means on said shaft, a pawl and ratchet means driven by said crank means for imparting an intermittent drive to said foil feeding means, said cam imparting a cutting stroke during a return stroke of the pawl.

4. The combination as claimed in claim 2, wherein said driving means comprises a cam shaft driven through said clutch means, said clutch means being normally open, an actuating element for closing the clutch, said actuating element being operated only when a bottle is present in the capping position.

5. The combination as claimed in claim 4, wherein the cam shaft is driven by bevel gears, one of said gears being secured to a clutch element, the other clutch element being secured to said actuating element comprising a vertically disposed spindle keyed to said gear pinion, said spindle being supported at its lower end on a pivotally mounted plate, said plate being moved to an operative position, when a bottle is present in the capping position.

6. The combination as claimed in claim 2, wherein the foil feeding means comprises feeding rolls for drawing the foil from a supply and feeding rolls for the scrap strip, said feeding rolls being driven from a common sprocket and chain gear, intermittently actuated from a cam shaft.

7. The combination as claimed in claim 6, wherein said feed rolls are carried by a bell mounting and are driven by gear trains including idle gears from said sprocket and chain gear, whereby the bell mounting and the gears carried thereby may be removed by unmeshing the gear trains at the idle gears.

8. The combination as claimed in claim 2, wherein the cap forming assembly is mounted for rotation relatively to said stationary spindle, index means being provided for holding said unit in its positions of rest relatively to said spindle.

9. The combination as claimed in claim 8, wherein the indexing means comprises an arcuate surface operatively associated with the cap forming assembly, a relatively stationary plate cooperating with said surface and means for locking the plate and surface together.

10. The combination as claimed in claim 9, wherein a stationary steadyng post is provided, said plate having an aperture engaging said post whereby the plate may be moved axially of the post in accordance with vertical adjustment of the capping heads.

11. The combination as claimed in claim 2, wherein a cap chute is removably mounted on the cap forming assembly to receive formed caps, said chute extending downwardly in a substantial vertical direction to a position for delivery of a cap to a bottle.

12. The combination as claimed in claim 2, wherein the cap forming die means comprises an upper assembly including a stationary die member, and a lower reciprocating punch actuated by rotary cam means.

13. The combination as claimed in claim 12, wherein the upper assembly includes an embossing die, a spring biased former, and a spring biased die ring and stripper ring located between said die and former.

14. The combination as claimed in claim 13, wherein said upper assembly is removable as a unit from mounting means and is held in operative position in said mounting by manually operable clamping means.

15. The combination as claimed in claim 2, wherein the cap forming die means comprises an upper assembly including a stationary die means and an embossing die, and a lower reciprocating punch actuated by rotary cam means, a complementary embossing element being slidably mounted in the punch under frictional control means.
